SELECTIVE SINGLE TRIGGER

Halvor Olsen Eiane, Washington Island, Wis.

Application August 19, 1943, Serial No. 499,277

7 Claims. (Cl. 42—42)

My invention relates to improvements in selective single trigger mechanism for double barrel guns; and the objects of my improvements are; first, to provide a selective single trigger mechanism capable of functioning without any co-operative action from the lock-mechanism of a gun; second, to so construct the trigger mechanism that firing of both barrels at the same time will be impossible; and third, to facilitate conversion of existing double barrel guns with double triggers to single trigger guns, with little or no discarding of old parts except old double triggers.

I attain these objects by the use of a novel trigger mechanism hereinafter more fully described and claimed, having reference to the accompanying drawing in which: Fig. 1 represents a side view of the whole trigger mechanism as mounted in a trigger plate, partly sectional. Fig. 2 is a side view of a trigger blade in detached relation. Fig. 3 is a rear view of the trigger blade shown in Fig. 2. Fig. 4 represents a rear view of a two-armed spring shifting lever in detached relation. Fig. 5 is a right side view of the lever shown in Fig. 4. Fig. 6 is a bottom view of a trigger body in detached relation and showing a hinge-pin in position. Fig. 7 is a top view of the trigger body shown in Fig. 6, and shows a pair of bridges across its milled out portion and a longitudinally disposed hinge-pin supported in the bridges. Fig. 8 represents a rear view of the trigger body in detached relation and carrying a hinged longitudinally disposed trigger blade in ready position for firing of a right gun barrel, while dotted lines indicate position of trigger blade for firing a left gun barrel. Fig. 9 is a rear view of a hinge-block for movably connecting the front portion of the trigger body to a trigger plate in hinged relation. Fig. 10 is a side view of the hinge-block shown in Fig. 9. Fig. 11 represents a side view of a pivotal selective lever provided with an integral formed stem. Fig. 12 is a side view of the selective lever shown in Fig. 11. Fig. 13 represents a bottom view of a pivotal action spring in detached relation, for imparting side-wise movements to the trigger blade. Fig. 14 is a side view of the action spring shown in Fig. 13. Fig. 15 is a rear view of one of a pair of bridges, for use across the main portion of the trigger body. Fig. 16 is an enlarged cross sectional detail view of a slot located at the lower end of the spring shifting lever shown in Fig. 4. Similar numerals refer to similar parts throughout the several views.

A, in Figs. 1, 6, 7 and 8, is a trigger body provided with a trigger grip 2 and longitudinal side walls 3. Across the upper portions of the side walls 3 are placed two bridges 4, of identical shape, and fitted into cuts or notches 5, so that

the bridges are flush with the upper portions of the side walls 3, and in this position the bridges 4 are then permanently welded or brazed to the side walls 3.

5 In the center of the bridges 4 is a passage 6, (shown in Fig. 15) through which a hinge-pin 7 is tightly inserted (see Fig. 7).

A trigger blade 8 is provided with a longitudinal passage 9 in its lower portion (shown in Fig. 3, and indicated by dotted lines in Fig. 2) through which the hinge-pin 7 is inserted, and thus, the blade 8 is movably attached to the trigger body A, in a longitudinal relation, so that the blade 8 can swing in a predetermined arc to right or left.

10 On each side of the trigger blade 8 are two integral formed stop-lugs 10—R and 10—L which bear against the upper surface of the bridges 4 when the blade 8 is either in its right or left position, and thus limit the movements of the blade 8 to the exact predetermined positions.

15 It will be noted in Fig. 3, that the trigger blade 8 is provided with a pair of cam-lugs 11—R and 11—L at its lower rearward corner, whose functional purpose will presently be explained.

20 At the upper rear corner of the trigger blade 8 is a round rearwardly pointing pivot stud 12, which is integral with the blade 8 and which fits a pivot hole or passage 13 in the upper end of a two-armed spring shifting lever 14, (see Fig. 4) while a semi-circular collar 15 on the lever 14 is turned into a recess 16, cut in the blade 8 and thus, the collar 15 retains the lever 14 in position by occupying the recess 16. A pair of 25 arms 17—R and 17—L extend from both sides of the lever 14 at its upper portion, while at the lower end of the lever 14 is a vertically disposed slot 18, as shown in Fig. 4.

25 Referring to Figs. 6 and 7, it will be noted that 40 a bearing hole 19 is provided in the bottom part or floor of the trigger body A, for pivotal mounting of a stem 20, which is an integral part of a selective lever 21. An action spring 22, provided with a terminal eye or sleeve 23 at its front end and a contact point 24 adjacent its rear end is placed partly under the bridges 4, so that the terminal sleeve 23 will be in alignment with the bearing hole 19, after which the stem 20 can be put through the bearing hole 19 and the sleeve 23; and during this stage of assembling, the 45 selective lever 21 is at right angle with the trigger body A, so that by a quarter turn, a tongue 25 on the lever 21 can occupy a segmental groove 26 in the trigger body A. It will be particularly noted that in Fig. 11, the stem 20 is provided with a short squared section 27, which fits tightly into a squared aperture 28 in the upper portion of the terminal sleeve 23; and with a nut 29 (shown in Fig. 1) to engage a threaded section 50 30 on the stem 20, the spring 22 is thus firmly

55

secured to the stem 20 and the selective lever 21. At the rear end of the spring 22 is a short section 31, which is rounded for reception by the slot 18 in the lower end of the spring shifting lever 14, but it will be borne in mind that the spring 22 is pivotally mounted and its movements describe part of a circle for which allowance in the slot 18 must be made in the form of funnel-shaped sides as shown in Fig. 16, in order to reduce the amount of play to a minimum.

The trigger body A is mounted in hinged relation to a trigger plate 32 through a hinge-block 33, which is provided with a threaded stud 34 that screws into the trigger plate 32. A crosswise passage 35 in the side walls 3 of the trigger body A, and a crosswise passage 36 in the hinge-block 33 (shown in Figs. 1 and 10) are drilled for reception of a hinge-pin 37, (see Fig. 6) which thus constitute the hinge arrangement for the trigger body A. The side walls 3 extend in bifurcated form beyond the hinge-pin passage 35, and are provided with downward pointed projections 38 which keep a pair of spiral springs 39 in place, (only one spring being shown in Fig. 1) while pockets 40 (of which there also are two) in the trigger plate 32, keep the lower ends of the spiral springs 39 in place, and thus maintain the trigger body A under spring pressure in a depressed normal position.

Referring to Fig. 1, it will be seen that a spring 41 is located behind the trigger blade 8 and secured by a screw 42 to the trigger plate 32, while at its forward and upper end is a centrally located interceptor point 43, which plays a dual functional part in the operation of the trigger mechanism.

When it is desired to fire, we say, the right barrel of a shot gun, the first thing done is to move the selective lever 21 toward the right which brings the contact point 24 on the spring 22 into contact with the cam 11-L on the trigger blade 8, and as the spring 22 exerts upward pressure, the blade 8 is then tilted over on its hinge to the right side and stopped by the lugs 10-R bearing against the bridges 4, and at this stage, the whole trigger mechanism is to all intent and purpose the same as a right side trigger of a gun with double triggers, but as a finger is pressed against the grip 2 and the trigger blade 8 is raised and contact made with a right side sear, a simultaneous contact is made by the arm 17-L on the spring shifting lever 14 against the interceptor point 43, and at the same time the right gun barrel is fired, the spring shifting lever 14 swings the rear end of the spring 22 over to the right side so the contact point 24 will press against the cam 11-R, but the trigger blade 8 is restrained by the interposing interceptor point 43 from tilting over to the left side until the trigger body A is in normal depressed position, when the trigger blade 8 can swing clear under the interceptor point 43.

It will thus be seen that the interceptor point 43 is the means of actuating the spring shifting lever 14 while the trigger mechanism is on its upward move and at the same time keeps the trigger blade 8 from swinging over to the opposite side before the return movement of the trigger mechanism is at normal depressed position. This arrangement is an insurance against involuntarily firing the second barrel.

The spring 41 is strong enough to actuate the spring shifting lever 14 without being raised, but is designed to raise a little and cushion the trig-

ger mechanism at the end of its upward movement. As heretofore pointed out, this trigger mechanism does not depend on any co-operative action from any other source, but derives all its functional operating power from its own springs and the squeeze of a gunner's trigger finger, and will fire each barrel alternately as long as desired.

Although the sears are no part of the present invention, I have shown portions of associate sears designated as 44-L and 44-R, merely to illustrate their relative positions with the trigger blade 8, as shown in Figs. 1 and 8.

The use of the letters L and R, indicate left and right respectively.

I do not intend to limit my invention to the exact descriptions and drawings as herein given, as many changes can be made without departing from the principles involved.

Having thus described my invention what I claim as new and desire to secure by Letters Patent is:

1. In a selective single trigger mechanism for double barrel guns, the construction therein comprising a hinged trigger body having bottom floor and vertically disposed side walls terminating in parallel bifurcated extensions, a transverse passage through said bifurcated extensions, a trigger plate having a slot-shaped aperture for operatively accommodating said trigger body, a hinge-block fixed to said trigger plate between said bifurcated extensions, a hinge-pin through said transverse passage and said hinge-block, a projecting point on the bottom side of each of said extensions and corresponding pockets in said trigger plate, a pair of spiral springs mounted in said pockets and retained under tension by said projecting points, a pair of bridges in fixed relation across said side walls, a trigger blade hinged to said bridges and movable in transverse relation to said trigger body, a curved trigger grip on said trigger body, means for effecting a selective position of said trigger blade, and means for effecting an alternate opposite position of said trigger blade in connection with each pull of said trigger.

2. In a selective single trigger mechanism for double barrel guns, the construction therein comprising a trigger body having bottom floor and vertically disposed side walls along said floor, a trigger plate having a slot-shaped aperture for accommodating said trigger body in hinged relation, a curved trigger grip underneath said bottom floor, a segmental groove in the front end of said grip, a vertically disposed passage through said floor, a selective lever provided with a pivotal stem and a segmental projecting tongue pivotally mounted in said passage and having an interlocked relation with said segmental groove, a pair of bridges across said side walls in permanent fixed positions, a longitudinal passage through said bridges relative to a center line in said trigger body, a trigger blade also provided with a longitudinal passage through its bottom portion, a hinge-pin through said longitudinal passages connecting said trigger blade to said bridges in hinged relation, a two-armed lever pivotally mounted on said trigger blade and movable in transverse relation to said blade, a double faced cam-lug on said trigger blade, an action spring fixed to said pivotal stem and in operative connection with said two-armed lever and in engageable contact with said double faced cam-lug, and associate means for co-ordinating up-

ward movement of said trigger body and blade with simultaneous interceptive action on said two-armed lever in effecting a reversed position of said action spring.

3. In a selective single trigger mechanism for double barrel guns, a trigger body having vertically disposed side walls and bottom floor, a trigger plate for hinged mounting of said trigger body, a selective pivot stem journalled through said floor, a trigger blade mounted in hinged relation to said trigger body, an action spring provided with a terminal sleeve fixed upon said pivot stem by means comprising a square formed section on said pivot stem, a complementarily square formed aperture in said sleeve, and a threaded section formed on said stem for receiving a threaded nut, an integrally formed double faced cam-lug extending from the right and left side of said trigger blade, a contact point adjacent to the rear end of said action spring engaging said double faced cam-lug, a two-armed lever having a slot formed at its lower end portion pivotally mounted on the upper rear portion of said trigger blade and movable in transverse relation to said blade, an operative connection between said slot and the rear end portion of said action spring, and means for co-ordinating upward movement of said trigger body with simultaneous interceptive action upon said two-armed lever effecting a reversed position of said action spring, said means comprising an interceptor spring secured to said trigger plate in a centerline position and provided with an elevated interceptor point arranged for intercepting one arm of said two-armed lever in alternate opposite shifting order.

4. In a selective single trigger mechanism for double barrel guns, a trigger body having vertical side walls and bottom floor, a trigger plate for receiving said trigger body in movably hinged relation, a pivot stem journalled through said floor, a pair of bridges fixed in crosswise relation to said side walls, a trigger blade having a double faced cam-lug movably hinged to said bridges, a two-armed lever pivotally mounted on said trigger blade, a slot formed at the lower end of said two-armed lever, an action spring fixed to said pivot stem and engaging said cam-lug and operatively connected to said slot, a pair of stop-lugs at each side of said trigger blade arranged to bear against said bridges and maintain said blade in a right or left inclined position, an interceptor spring provided with an elevated projecting interceptor point centrally fixed to said trigger plate, and a pair of associated sear members arranged to be engaged by said trigger blade in alternate opposite order.

5. In a selective single trigger mechanism for double barrel guns, a trigger body having vertically disposed side walls and bottom floor, a trigger plate for receiving said trigger body in movably hinged relation, a selective pivot stem journalled in said bottom floor, a pair of bridges in permanent fixed position across said side walls, a trigger blade hinged to said bridges and movable in transverse relation to said trigger body, a double faced cam-lug on said trigger blade, a two-armed lever pivotally mounted on said trigger blade, an action spring connected in fixed relation to said selective pivot stem and in operative engagement with said double faced cam-lug and said two-armed lever, an interceptor spring fixed in lengthwise central relation to said trigger plate, an elevated interceptor point at the

front end of said interceptor spring and in central overhead position relative to the hinged position of said trigger blade, a pair of associate sear members, said trigger body and blade arranged for hinged movement from a normal low position to an elevated high position to effect contact and release of one of said sear members and simultaneously effect a reversed position of said action spring through means of said two-armed lever in interceptive action against said interceptor point and to interpose restraint against side movement of said trigger blade by means of said interceptor point prior to resumption of normal position of said trigger body.

6. In a selective single trigger mechanism for double barrel guns, the construction therein comprising a trigger body having vertically disposed side walls and bottom floor, a trigger plate for receiving said trigger body in movably hinged relation, a coiled spring arrangement for maintaining said trigger body under spring pressure in normal depressed position, a selective pivot stem journalled through said bottom floor, a pair of bridges fixed in permanent position across said side walls, a trigger blade connected in hinged relation to said bridges and movable in transverse relation to said trigger body, a two-armed lever pivotally mounted on said trigger blade through means comprising an integral formed pivot stem on said trigger blade and a recessed collar seat adjacent to said integral pivot stem and a complementarily formed sleeve on said two-armed lever embracing said integral formed stem and a semi-circular collar on said sleeve occupying said collar seat, a pair of stop-lugs at each side of said trigger blade arranged to bear against said bridges and maintain said blade in either a right or a left inclined position with respect to said trigger body, a double faced cam-lug on said trigger blade, an action spring fixed to said selective pivot stem and engageable with said cam-lug and in operative engagement with said two-armed lever, and a centrally fixed interceptor interposed in the path of said two-armed lever arranged to transform upward movement of said trigger body into transverse movement of said two-armed lever to effect reversal of position of said action spring and restrain sidewise movement of said trigger blade until return of said trigger body to a normal depressed position.

7. In a selective single trigger mechanism for double barrel guns, the combination of a selective pivotal lever with an independent acting trigger mechanism comprising a trigger plate, a trigger body hinged to said plate, a pair of bridges on said trigger body, a trigger blade hinged to said trigger body, a two-armed lever pivotally connected to said trigger blade, a double faced cam-lug on said trigger blade, an action spring fixed to said selective lever and in engagement with said double faced cam-lug and in operative connection with said two-armed lever, an interceptor on said trigger plate, and a pair of associate sear members, all constructed and arranged for effecting a selective position of said trigger blade and for effecting a regular reversed position of said trigger blade in alternate order through interceptive actions derived from each upward movement of said trigger body and to effect contact and to effect release of one of said sear members in alternate order from self contained derivative actions of said trigger mechanism.
